DESIGN FOR A BOTTLE OR SIMILAR ARTICLE

Edward M. Lawrence, Lancaster, Ohio

Application April 28, 1939, Serial No. 84,649

Term of patent 3½ years

To all whom it may concern:

Be it known that I, Edward M. Lawrence, a citizen of the United States, residing in Lancaster, county of Fairfield, State of Ohio, have invented a new, original, and ornamental Design for a Bottle or Similar Article, of which the following is a specification, reference being had to the accompanying drawing, forming a part thereof.

The figure is a perspective view of a bottle or similar article, illustrating my new design.

The appearance of the opposite side of the bottle or similar article is substantially the same as the side shown herein.

I claim:

The ornamental design for a bottle or similar article, substantially as shown and described.

EDWARD M. LAWRENCE.
